UNITED STATES PATENT OFFICE.

PERCY R. LEA, OF SAN FRANCISCO, CALIFORNIA.

SAFETY ATTACHMENT FOR AEROPLANES.

1,175,363.

Specification of Letters Patent.

Patented Mar. 14, 1916.

Application filed October 7, 1914. Serial No. 865,472.

To all whom it may concern:

Be it known that I, PERCY R. LEA, a citizen of the United States, residing at San Francisco, in the county of San Francisco, State of California, have invented a new and useful Safety Attachment for Aeroplanes, of which the following is a specification, in such full and clear terms as will enable those skilled in the art to construct and use the same.

This invention relates to a safety attachment for aeroplanes and its object is to provide means whereby the aeroplane may be caused to be righted and land safely even though an accident may happen to its operating mechanism.

An object of the invention is to provide means whereby the righting apparatus will be folded up and will occupy as little space as possible, thereby reducing wind resistance when the aeroplane is in motion.

Other objects of the invention will appear as the description proceeds.

An embodiment of the invention is shown in the drawing in which the same reference numeral is applied to the same portion throughout, but I am aware that there are many modifications thereof.

Figure 1 is a front elevation of a conventional form of biplane having this invention applied thereto, Fig. 2 is a front elevation of one of the safety attachments, Fig. 3 is a view in elevation of one of the safety attachments with a portion of the fabric thereof broken away for purposes of illustration and looking at right angles to Fig. 2, Fig. 4 is a plan view of the end of one of the planes showing the position of the safety attachment with respect thereto, Fig. 5 is a plan view of a portion of the lower plane showing the hook for holding the safety attachment in the closed and inoperative position, Fig. 6 is a view in perspective of a portion of the disk used for rotating the safety attachment to the operative position, Fig. 7 is a view in perspective of one of the arms which holds the safety attachment to the disk which rotates the same, and Fig. 8 is a view partly in section of the lug on the rotating disk and a portion of one of the arms in place thereon.

The numeral 1 represents the lower plane, 2 the upper plane and 3 suitable frame work connecting the two planes and bracing them. The safety attachment comprises a pair of parachutes 4 and 5 with their operating

mechanism. Each parachute is substantially the same as the other so that a description of only one will be given.

The parachute is supported by means of a pair of arms 7 and 8 suitably connected to the upper plane and extending outwardly therefrom a short distance. The arms 7 and 8 support a disk 9 which disk has lugs 10 and 11 at diametrically opposite portions thereon and it has a pin 12 which is connected with a rod 13 having a spring 14 connected thereto and secured at its lower end to a ring 15 on the lower plane.

The disk supports a rod 16 having two arms 17 and 18 connected therewith by means of the lugs 10 and 11. The lugs 10 and 11 have a notch cut therein as indicated at 20, Fig. 6, while the arms 17 and 18 have an interior lug 21 which fits into the notch 20 to permit the parachute rod 16 to move a slight distance at right angles to the axis of the disk.

Connected with the underside of the upper plane are two cam rods 22 and 23. The rods 22 and 23 have offsets at 24 and 25 and are rigidly connected with a shaft 26 on which the disk 9 turns, the object being to pull the slideable collar 27 up to the disk and thereby through the spring 28 pull the cup 29 off the ends of the ribs 30 of the parachute.

The parachute has its fabric 31 connected with a series of ribs 30 in a well known manner, and said ribs are pivoted to a fixed collar 33 on the rod 16. Four of the ribs are also connected with rods 34, which rods are pivotally connected with a slideable plate 35 on the rod 16 and which plate has a spring 37 bearing thereon. The object of the spring 37 is to push the plate 35 away from the collar 33 and thereby cause the parachute to open. The rod 16 is long enough to prevent the plate 35 from passing off when the parachute opens and when the parachute is closed a hook 38 pivoted on the lower plane secures the parachute in the position shown in Fig. 1. This hook has a spring 39 connected therewith and with the bottom plane to hold the hook in position against the rod 16 and a cable 40 is connected therewith and extends around a pulley 41 to a lever 42 pivoted on the frame at 43 within convenient reach of the operator to enable him to release the hook when required.

The operation of the apparatus is as fol-

lows: As soon as it becomes necessary from any cause to make use of the safety apparatus the operator pulls on the two levers 42, whereupon the hooks will release each of the parachutes and the two springs 14 will rotate the two disks 9 through an angle of about 180 degrees during which rotation the cup 29 will be pulled off the ends of the parachute ribs. Also during this rotation the slideable collar 27 will pass out of contact with the rods 22 and 23 and thereafter will be inoperative, while during the act of rotating 180 degrees the parachute will be caused to be opened by the spring 37 pushing the plate 35 outwardly and carrying along with it the ribs to which it is connected. It is, of course, assumed that the parachute is braced to withstand the necessary strains, but which forms no part of the present invention.

It is to be observed that while the spring 14 has been illustrated for the purpose of rotating the parachutes into the operative position, that any other means might be used for this purpose, and it is not my intention to be limited by a spring operating mechanism at this point.

Having thus described my invention what I claim as new and desire to secure by Letters Patent of the United States, is as follows, modifications within the scope of the claims being expressly reserved:

1. The combination with an aeroplane, of a parachute at each end of the aeroplane, means to carry said parachutes normally in a closed position with their tops downward, manual means for releasing the parachutes, means to rotate the parachutes through a considerable angle when released, mechanical means for releasing the parachute ribs when being turned from the inoperative position to the operative position, and mechanical means for opening the parachutes when being so turned.
2. The combination with an aeroplane, of a parachute pivotally secured at each end of the aeroplane, means to secure each of said parachutes in a closed position with the top

of the parachutes down, manual means for releasing the parachutes, and mechanical means for turning each of them through substantially 180 degrees to bring them to a position to support the aeroplane.

3. The combination with an aeroplane, of a parachute pivotally secured at each end thereof, locks for securing both of said parachutes with their tops downward in a closing position, means carried by each parachute to open them when released, and means to rotate each parachute through substantially 180 degrees when released.

4. The combination with an aeroplane, of a parachute pivotally secured at each end of the aeroplane, locks for securing both of said parachutes with their tops downward in a closed position, means to hold the parachute ribs adjacent the parachute standard when the parachute is in the inoperative position, a cam to release the parachute ribs as the parachute is being turned from the inoperative to the operative position, and a spring at the top of the parachute to open the same when the ribs are released.

5. The combination with an aeroplane of a parachute pivotally secured to the upper portion thereof, at each end of the same, means to lock said parachutes with their tops downward and with their ribs in the closed position, means to secure the parachute ribs in the closed position when the parachute is locked with its top downward, means to release said ribs when the parachute is being turned from the inoperative to the operative position, means to open the parachute after the ribs are released, and means whereby the parachute may swing in a plane parallel to the normal line of travel of the aeroplane.

In testimony whereof I have hereunto set my hand this 30th day of September A. D. 1914, in the presence of the two subscribed witnesses.

PERCY R. LEA.
